STANLEY M. HALSTEAD AND ANTON I. WICKLAND, OF SAN JOSE, CALIFORNIA.

ELEVATOR.

Application filed October 19, 1926. Serial No. 142,630.

This invention relates particularly to that type of elevators wherein fluid pressure is utilized to actuate a vertically movable piston, reference being made to our copending application Serial No. 115,542, filed June 12, 1926, patented January 18, 1927, No. 1,614,790.

It is one object of the present invention to provide an elevator of the character indicated wherein the fluid is introduced into the cylinder and piston in such a manner as to simplify its construction, reduce the amount of material required in its construction, and in which the fluid pressure is applied in the simplest and most direct manner.

It is also an object of the invention to provide a structure of the character indicated wherein a simple and effective means is provided for positioning the fixed cylinder, and a self centering means inserted between the fixed and revoluble cylinders.

In the drawing.—

Figure 1 is a vertical transverse section 25 through a structure embodying our invention taken on line 1—1 of Figure 2.

Figure 2 is a plan view of the structure, parts being broken away.

Figure 3 is a section on line 3—3 of Figure 1.

Referring now more particularly to the drawing, we show at 1 a cylindrical pipe of suitable diameter having an annular member 2 mounted on its upper end, the inner 35 perimeter 3 of the said member forming a bearing as hereinafter described. A bottom member 4 is mounted upon the lower end of the pipe 1 as shown, this member 4 being threaded at 5 to receive a supply pipe 6 and having an upstanding concentrically arranged boss 7 formed thereon with a spherical recess 8 formed in its upper surface as shown. A conduit 9 connects the pipe 6 with the recess 8. In the pipe 6 is inserted 45 a T 10 in such a manner that the axis of the head portion of the said T is coincident with the axis of the member 4, and into the lower end of the T is mounted a pin 11.

In positioning the cylinder 1 a suitable 50 hole as 12 is made in the ground and the said cylinder placed vertically therein resting upon the pin 11. When the pin 11 has been driven into the ground a distance to bring the top of the cylinder to the desired level the space between the cylinder 1 and

the walls of the hole 12 is filled with concrete.

At 13 we show a second cylinder of less diameter than the first cylinder and provided with a slightly tapering upper portion 60 14 carrying an outwardly extending flange 15 adapted to engage the bearing surface 3 of member 2. A bottom member 16 is mounted upon the lower end of the cylinder 13, this member having a conduit 17 formed 65 in its axis of rotation. An upstanding pipe 18 is concentrically mounted in its upper surface in communication with the conduit 17, and a semi-spherical foot is concentrically mounted upon its lower surface as at 19 and 70 provided with a conduit 20. When this cylinder 13 is inserted in cylinder 1 it is automatically centered by the foot 19 engaging recess 8 and the flange 15 engaging bearing surface 3. When in this position 75 the pipe 6 communicates at all times with pipe 18 through conduits 9, 20 and 17 and yet the cylinder 13 is permitted to rotate freely in cylinder 1.

A piston is shown at 21, the same being 80 hollow and having a concentrically arranged orifice in its lower end as at 22 to permit the passage of pipe 18 therethrough and the passage of liquid from the piston to the cylinder 13. This piston has an outside diameter substantially equal to the inner diameter of the upper end of the cylinder 13, and a head 23 closely fitting the cylinder 13. On the closed upper end of the piston 21 is mounted any suitable head such as shown 85 at 24.

When the elevator has been constructed and assembled as described the piston is elevated by forcing a liquid under pressure into piston 21 and thence through the orifice 95 22 into cylinder 13 where it is applied against the piston head 23 to move it upwardly. When the pressure of the liquid is released the piston descends thereby forcing the fluid in cylinder 13 back into the 100 piston 21. The construction is such that the piston may be reciprocated at will, and yet through the construction of the fixed and revoluble cylinders 1 and 13 it may also be rotated as desired without interrupting the 105 flow of liquid through the conduits to the interior of the cylinder.

It is to be understood, of course, that while we have herein shown and described but one specific embodiment of our inven- 110

tion, changes in form, construction and method of assembly and operation may be made in the scope of the appended claims.

We claim:—

5. 1. An elevator of the character described comprising a fixed vertical cylinder, a non-reciprocating hollow cylinder removably mounted therein and closed against communication therewith, a piston mounted to reciprocate in said second cylinder, and a supply conduit formed in the adjacent bottom ends of the two cylinders and concentrically arranged relative thereto.
10. 2. An elevator of the character described comprising a fixed vertical cylinder, a second cylinder concentrically mounted therein and having an annular bearing contact therewith at its upper end and a pivotal

bearing thereon at its lower end, a conduit entering the second cylinder through said 20 pivotal bearing, and a piston mounted to reciprocate in said second cylinder.

3. An elevator of the character described comprising a fixed vertical cylinder, a second cylinder revolvably mounted therein, a 25 hollow piston closed at its upper end and having an orifice in its lower end mounted to reciprocate in said second cylinder, and a supply conduit formed in the adjacent bottom ends of the two cylinders and concentrically arranged relative thereto and passing upwardly through the orifice in said piston to a point above the lower end of the piston when said piston is fully extended.

STANLEY M. HALSTEAD.
